DESIGN FOR A PEDESTAL CABINET

Philip D. Parsons, Swarthmore, Pa., assignor to Scott Paper Company, Chester, Pa., a corporation of Pennsylvania

Application August 22, 1941, Serial No. 102,992

Term of patent 7 years

To all whom it may concern:

Be it known that I, Philip D. Parsons, a citizen of the United States, residing in Swarthmore, Delaware county, Pennsylvania, have invented a new, original, and ornamental Design for a Pedestal Cabinet, of which the following is a specification, reference being had to the accompanying drawing, forming part thereof, in which:

The single figure is a perspective view of a pedestal cabinet showing my new design.

I claim:

The ornamental design for a pedestal cabinet, substantially as shown.

PHILIP D. PARSONS.
